UNITED STATES PATENT OFFICE.

ALEXANDER HARRISON, OF TERRE HAUTE, INDIANA, ASSIGNOR OF TWO-THIRDS TO PETER N. STAFF AND GEORGE L. NEWTON, OF SAME PLACE.

DESIGN FOR A BADGE.

SPECIFICATION forming part of Design No. 25,304, dated March 31, 1896.

Application filed February 8, 1896. Serial No. 578,613. Term of patent 3½ years.

To all whom it may concern:

Be it known that I, ALEXANDER HARRISON, a citizen of the United States, and a resident of Terre Haute, in the county of Vigo and State of Indiana, have invented and produced a new and original Design for a Badge, of which the following is a specification, reference being had to the accompanying drawings, forming part thereof.

Similar letters of reference refer to similar parts throughout the drawings.

Figure 1 is a front view of my newly-invented design for a badge. Fig. 2 is a view of the back of my design for a badge.

The leading features of my design consist, first, in a rectangular or oblong frame A, into which are cut two rectangular openings a and a', through each of which a panel placed behind the frame A may be seen, and a long slit b extending across the bottom of the frame

A, through which a ribbon C is sewed, and, second, a facsimile of a broom, the handle h of which extends perpendicularly across the middle of the frame A, between the openings a and a', and the broom extends upward and above the frame A, as shown in the drawings. The two lateral edges of the frame A are bent back for the purpose of clasping and holding panels, cardboards or other similar articles behind the frame A, as shown in Fig. 2.

30

I claim—

The design for a badge herein described and shown.

In testimony that I claim the foregoing as my own I affix my signature in the presence 35 of two witnesses.

ALEXANDER HARRISON.
